UNITED STATES PATENT OFFICE.

WILLIAM C. BLUNDELL, OF LOS ANGELES, CALIFORNIA, ASSIGNOR OF ONE-HALF TO
EUGENE W. BLUNDELL, OF LOS ANGELES, CALIFORNIA.

STEAM AND WATER GOVERNOR FOR BOILERS.

Application filed July 19, 1924. Serial No. 726,999.

To all whom it may concern:

Be it known that I, WILLIAM C. BLUNDELL, a citizen of the United States, residing at Los Angeles, in the county of Los Angeles and State of California, have invented new and useful Improvements in Steam and Water Governors for Boilers, of which the following is a specification.

This invention is a steam and water governor for boilers, and consists of the novel features herein shown, described and claimed.

An object is to make a device to be used in combination with a boiler and steam pump for feeding the boiler and serving to turn on the steam to operate the pump to feed the boiler when the water level in the boiler goes below a pre-determined point.

Another object is to provide an automatic safety device for blowing a whistle when the steam and water governor fails to work.

Another object is to provide a plurality of boilers with a steam and water governor for each boiler and connect all the governors to a single feed water pumping system.

Other objects and advantages will appear from the drawings and specification.

The drawings illustrate the construction and use of a steam and water governor for boilers embodying the principles of my invention.

Figure 1 is a side elevation of a boiler provided with a feed water pump and my steam and water governor for controlling the pump.

Fig. 2 is a detail end elevation looking in the direction indicated by the arrows 2 in Figs. 1 and 6.

Fig. 3 is a cross sectional detail on the lines 3-3 of Figs. 1 and 5 and looking in the direction indicated by the arrows.

Fig. 4 is a cross sectional detail on the line 4-4 of Figs. 1 and 5.

Fig. 5 is an enlarged side elevation of the steam and water governor shown in Fig. 1 and as seen looking in the direction indicated by the arrow 5 in Fig. 6.

Fig. 6 is a horizontal section on the line 6-6 of Fig. 5 and looking downwardly as indicated by the arrows.

Fig. 7 is a bottom plan view as indicated by the arrow 7 in Fig. 5, parts being broken away and shown in section.

Fig. 8 is a diagrammatic top plan view of a plurality of boilers, each boiler being provided with a governor and all the governors connected to a single feed water pump system.

The details of construction and operation shown in the drawings are as follows:

The steam boiler 1 has a steam dome 2 and a steam water pump 3. It is desired to maintain the level in the steam boiler 1 at the line 4. The steam supply pipe 5 leads from the top of the dome 2 through a T 6 and valve 7. A branch pipe 8 leads downwardly from the T 6 to the water column 9 and gauge 10. A pipe 11 leads downwardly from the water column 9 to a valve 12 and is connected into the boiler at 13 so that the water level in the boiler 1 will show on the gauge 10.

A pipe 14 leads from the top of the steam dome 2 through a T 14^a and through a valve 15 and T 16 to the steam chamber of the water pump 3. When the governor is working the valve 15 is closed. The pipe 17 leads from the water pump 3 through a T 18 and valve 19 and is connected into the boiler 1 at 20. When the governor is working the valve 19 is closed.

The steam and water governor 21 is connected to the pipes 8, 11, 14 and 17 and to the T 16, and the details are as follows:

The spacing spider 22 has arms 23, 24, 25 and 26 extending from a central hub 27, and the spacing rod sleeves 28, 29, 30 and 31 extend through the outer ends of the arms and the expansion tube 32 extends freely through the hub 27. A second spider 33 has arms 34, 35, 36 and 37 against which the ends of the sleeves 28, 29, 30 and 31 fit and the connecting rods 38, 39, 40 and 41 are inserted through the outer ends of the arms 34, 35, 36 and 37 and through the sleeves 28, 29, 30 and 31. A head 42 fits against the opposite ends of the sleeves 28, 29, 30 and 31 from the spider 33 and the rods 38, 39, 40 and 41 are tapped into the head 42 and screwed tight to hold the parts rigidly together. A lug 43 is formed integral with the spider 33 to occupy a vertical position and the lug is cored to form a chamber 44. The expansion tube 32 is tapped into the upper part of the lug 43 to communicate with the chamber 44 and a pipe 45 is tapped into the lower end of the lug 43 and extends downwardly.

through a cut off valve 46 and laterally to a **T** 47 incorporated into the pipe 11 above the valve 12, the parts being adjusted so that the water level line 4 will be within the cross sectional area of the expansion tube 32, or so that when the water level is high the expansion tube 32 will be full or nearly full of water, and so that when the water level is low the expansion tube 32 will be nearly or quite empty of water. The expansion tube 32 extends freely through the head 42.

The head 42 is a part of a casting cored to form an inlet steam chamber 48, an outlet steam chamber 49, an inlet water chamber 50, and an outlet water chamber 51. A pipe 52 connects the pipe 14 through the **T** 14^a and a valve 53 to the inlet steam chamber 48. A pipe 54 connects the outlet steam chamber 49 through a valve 55 to the **T** 16. A pipe 56 connects the inlet water chamber 50 through a valve 57 to the **T** 18 and pipe 17. A pipe 58 connects the outlet water chamber 51 through a valve 59 to the boiler 25 1 as indicated at 60. A valve seat and support 61 separates the inlet steam chamber 48 from the outlet steam chamber 49. A valve 62 fits the valve seat 61 and the valve stem 63 extends out of the chamber 48 through a stuffing box 64 and has a screw threaded outer end 65 extending through a cross head arm 66 with a nut 67 upon the outer end 65 to adjust the parts.

A valve seat 68 and support separates the water inlet chamber 50 from the water inlet chamber 51. A valve 69 fits the valve seat 68 and a valve stem 70 is connected to the valve 69 and extends out of the chamber 50 through a stuffing box 71 and has a screw threaded outer end 72 extending through the cross head arm 73 and a nut 74 upon its outer end. The cross head arms 66 and 73 are formed integral with a fitting 75 having a vertical chamber 76 and the expansion tube 32 is tapped into the upper end of the fitting 75 to communicate with the chamber 76. A pipe 77 leads from a **T** 78 in the pipe 8 through a valve 79 and is tapped into the fitting 75 to communicate with the chamber 76 so that when the boiler is operating steam will pass through the pipe 8, the **T** 78, the pipe 77, and the valve 79, to the chamber 76 and meet the water in the expansion tube 32, so that as the water goes up in the boiler the expansion tube 32 may fill with water and as the water goes down the expansion tube may fill with steam, and so that when the expansion tube 32 fills with steam more or less the tube will expand and move the fitting 75 and cross head arms 66 and 73 to unseat the valves 62 and 69, thereby turning steam into the steam chambers of the pump 3 to operate the pump, and so that when the pump operates water will flow through the pipe 17, the **T** 18, the pipe 56, and valve

57 to the chamber 50 and then to the chamber 51 and through the pipe 58 and valve 59 to the boiler 1, and as the water continues to flow the steam will be forced out of the expansion tube 32 and the expansion tube 70 will be filled more or less with water and will contract to reseat the valves 62 and 69, and this operation will continue as the water level goes up and down in the boiler.

A secondary expansion tube 80 is tapped into the lug 43 to communicate with the chamber 44 and extends into position near the casting carrying the head 42. A flexible tube 81 is connected to the free end of the secondary expansion tube 80 by a connection 82 and is connected to the fitting 75 by a connection 83. The tube 81 is bent to form a U-shaped portion at its center so that the tube may yield under the expansion and contraction of the expansion tube 80. In case the expansion tube 32 and co-operating parts fail to work the water level may go down until the secondary expansion tube 80 is filled with steam more or less.

A suitable compression valve 84 is connected by a pipe 85 to the steam chamber 49 and a whistle 86 is connected to the valve. The operating stem 87 of the valve is spring pressed outwardly and the valve is opened to blow the whistle by pressing the stem 87 inwardly. A slide 88 is loosely mounted on the expansion tube 32 and has a clamp 89 rigidly bolted to the secondary expansion tube 80 so that the slide 88 will be moved as the tube 80 expands or contracts. An arm 90 extends upwardly and laterally from the slide 88. A screw 91 is adjustably mounted through the upper end of the arm and held in adjusted position by a lock nut 92, the head 93 of the screw being in position to engage the stem 87 and the screw being accurately adjusted to blow the whistle 86 when the expansion tube 80 is filled with steam and expands.

The parts should be set up so that the expansion tube 32 will incline slightly downwardly from the steam end toward the water end so that when the water level goes down the water will all run out of the expansion tube instead of being trapped in the tube.

The boilers 94, 95 and 96 are each provided with a governor 97, 98 and 99 and the boilers are each connected to a steam pipe line 100 and to a feed water line 101. The steam pipe line leads from the boiler to the steam engines 102 and 103 and the engines 102 and 103 operate the pumps 104 and 105. I have shown two steam pumps for the reason that under some conditions the rules require two pumps so that either pump may be used while the other is shut down for repairs. The water line 101 is connected to the pumps 104 and 105. When the water becomes low in either of the boilers

94, 95 or 96 the steam line and water line will be open to operate a pump to raise the water level in that boiler.

Various changes may be made without departing from the spirit of the invention as claimed.

I claim:

1. The combination with a steam boiler and feed water pump, of an expansion tube 10 mounted at the desired water level, one end of the tube being connected to the boiler below the water level and the other end of the tube being connected to the boiler above the water level, a steam pipe connecting the 15 boiler to the pump and having a valve adapted to be opened and closed by the expansion and contraction of the expansion tube, and a water pipe connecting the pump to the boiler and having a valve adapted to be 20 opened and closed by the expansion and contraction of the expansion tube.

2. The combination with a steam boiler and feed water pump, of an expansion tube mounted at the desired water level, one end 25 of the tube being connected to the boiler below the water level and the other end of the tube being connected to the boiler above the water level, a steam pipe connecting the boiler to the pump and having a valve adapted to be 30 opened and closed by the expansion and contraction of the expansion tube, a water pipe connecting the pump to the boiler and having a valve adapted to be opened and closed by the expansion and contraction 35 of the expansion tube, a secondary expansion tube mounted below the desired water level and having one end connected to the boiler above the water level and the other end connected to the boiler below the 40 water level, a whistle connected to the boiler above the water level, and means carried by the secondary expansion tube for operating the steam whistle.

3. A steam and water governor for boilers 45 comprising an expansion tube adapted to be mounted at the desired water level with one end connected to the steam zone and the other end connected to the water zone of a boiler, valves operated by the expansion tube 50 and adapted to control a steam pipe connec-

tion from a boiler to a pump, and a water pipe connection from the pump to the boiler.

4. A steam and water governor for boilers comprising an expansion tube mounted in approximately horizontal position adjacent 55 the desired water level in the boiler, means connecting one end of the tube to the boiler below the water level, means connecting the other end of the tube to the steam space of the boiler, whereby steam and water can be 60 admitted to the tube upon the fall and rise of water in the boiler respectively to expand and contract the tube, and a valve controlling the water inlet to the boiler mechanically operated by the expansion and contraction 65 of the tube.

5. A steam and water governor for boilers comprising a plurality of boilers, a single steam pump system for the plurality of boilers, and a governor for each boiler, each 70 governor comprising an expansion tube adapted to be mounted at the desired water level with one end connected to the steam zone and the other end connected to the water zone of a boiler, valves operated by 75 the expansion tube and adapted to control a steam pipe connection from the boiler to the pump system, and a water pipe connection from the pump system to the boiler.

6. A steam and water governor for boilers 80 comprising an expansion tube mounted in approximately horizontal position adjacent the desired water level in the boiler, means connecting one end of the tube to the boiler below the water level, means connecting the other end of the tube to the steam space of the boiler, whereby steam and water can be 85 admitted to the tube upon the fall and rise of water in the boiler respectively to expand and contract the tube, a valve controlling 90 the water inlet to the boiler operable by the expansion and contraction of the tube, and a second valve controlling the steam supply from the boiler to the feed water pump of 95 the boiler operable simultaneously with the first valve by the expansion tube.

In testimony whereof I have signed my name to this specification.

WILLIAM C. BLUNDELL.
